[57] CLAIM

The ornamental design for a toe and finger wrap, as shown and described.

DESCRIPTION

FIG. 1 is a side, front perspective view of a toe and finger wrap;

FIG. 2 is a top, bottom or side plan view thereof;

FIG. 3 is a front view thereof;

FIG. 4 is a rear view thereof; and,

FIG. 5 is a side, front perspective view of a toe and finger wrap placed over a person's toe.

The broken line showing of the toes in FIG. 5 is for illustrative purposes only and forms no part of the claimed design.
